UNITED STATES PATENT OFFICE.

BEDFORD WOODSFORD, OF CHELSEA, LONDON, ENGLAND.

POCKET-FASTENER.

SPECIFICATION forming part of Letters Patent No. 412,906, dated October 15, 1889.

Application filed April 29, 1889. Serial No. 309,123. (No model.)

To all whom it may concern:

Be it known that I, BEDFORD WOODSFORD, of 118 King's Road, Chelsea, London, in the county of Middlesex, England, have invented 5 certain new and useful Improvements in Pocket-Fasteners; and I do hereby declare that the following is a full, clear, and exact description of the same.

My invention relates to improvements in 10 fasteners for securing the mouths or openings of pockets; and it has for its object the better protection of articles carried in the said pockets. I attain this object by the device illustrated by the accompanying drawings, in 15 which—

Figure 1 is a view in elevation of the fastener open. Fig. 2 is a view in plan thereof; and Figs. 3 and 4 are views in transverse section on lines *v w*, showing the fastener open 20 and closed, respectively.

Throughout the views similar parts are marked with like letters of reference.

The fastener consists of a band of spring-steel or other suitable material of a suitable 25 size to fit the mouth or opening of the pocket. For convenience in attaching to the pocket I prefer to make the band in two parts, as illustrated, the ends being adapted to engage with or slide in each other. The back part 30 A carries the engaging hook or snap *B*, and in the front part *A'* is formed the eye or catch *C*, with which the hook or snap *B* engages when the fastener is closed. On the plate *A* is riveted a light frame *A*², to which is hinged 35 by the pin *b* the hook or snap *B*, on which is fixed or formed a button *B'*. Into the back of the button *B'* is formed or fixed a short projection *b'*, the function of which is to press against the body when the button is pressed in to 40 open the fastener, thus giving the wearer notice that the pocket is being surreptitiously opened. The frame *A*² is adapted to form a guard for the button *B'*, so that accidental pressure may not release the hook or snap 45 and open the fastener. In the plate *A'* is a notch forming the eye or catch *C*, adapted to receive the hook or snap *B* and keep the two parts *A* and *A'* of the band together. A bowed plate *c* is riveted or otherwise fixed 50 over the catch or eye *C* to inclose it and provide free engaging space for the hook or snap *B*. A small spring *b*² is provided to keep the

hook or snap *B* forward to engage with the eye or catch *C*, and the engaging part of the said hook or snap is slightly curved to better 55 enable it to engage with the said eye or catch. It will thus be seen that to open a pocket fitted with this fastener the button *B'* must be pressed inward, when the pocket will fly open, and to close it it is only necessary to 60 press the band of the pocket containing the fastener against the body.

With this fastener I prefer to use a lining to the pocket composed of steel-chain, so that the contents of the pocket cannot be 65 abstracted by cutting the pocket open; but I lay no claim to such a device.

I do not limit myself to any particular method of fixing this fastener in a pocket; but I prefer to insert the parts *A* and *A'* in 70 the welt or band in a manner well known to tailors.

I wish it to be understood that I do not limit myself to the exact details of construction hereinabove described, and illustrated 75 by the accompanying drawings, but hold myself at liberty to make such changes and alterations as fairly fall within the spirit and scope of my invention; but

What I claim as my invention, and desire 80 to secure by Letters Patent, is—

1. In a pocket-fastener, the combination, with the back plate *A* and the front plate *A'*, of the bowed plate *c*, secured to the front plate, the frame *A*², secured behind the back 85 plate, and the locking-hook pivoted to said frame and adapted to engage with the front plate, substantially as set forth.

2. In a pocket-fastener, the combination, with the back plate *A* and the front plate *A'*, 90 of the frame *A*², secured behind the back plate, and the locking-hook pivoted to said frame at its lower end and provided with a rearward projection *b'* at its upper end adapted to press against the body of the wearer 95 and give warning when the pocket is being opened, substantially as set forth.

In witness whereof I have hereunto signed my name in the presence of two subscribing witnesses.

BEDFORD WOODSFORD.
